UNITED STATES PATENT OFFICE.

ALPHEUS FAY, OF LOUISVILLE, KENTUCKY.

AERATING BUTTER-SEPARATOR.

1,019,235.

Specification of Letters Patent.

Patented Mar. 5, 1912.

Application filed June 7, 1911. Serial No. 631,840.

To all whom it may concern:

Be it known that I, ALPHEUS FAY, a citizen of the United States, and resident of Louisville, in the county of Jefferson and State of Kentucky, have invented a certain new and useful Aerating Butter-Separator, of which the following is a specification.

My invention relates to butter separators of the aerating type, and its object is to provide a simple device of this character, of increased efficiency, for separating the butter from the non-fatty milk elements by an aerating and agitating action, and which will be adaptable readily to different conditions met with in such treatment.

My invention consists in the provision of a novel construction of the dasher or agitator, and in improved relative arrangement of the dasher and brake, as well as in improved means for imparting motion to the mechanism, whereby the liquid acted upon is utilized as a medium in the distribution of the energy applied to the driving of the separator.

My invention also consists in the details of construction and arrangement, as will hereinafter be more fully described and claimed.

In the drawings: Figure 1 is a sectional elevation of a device embodying my invention. Fig. 2 is a detail plan view of part of one of the brake arms. Fig. 3 is a vertical section of the dasher or agitator, the upper part, as well as the agitator shaft, being in elevation. Fig. 4 is a sectional plan view of said agitator. Fig. 5 is a perspective view of part of the agitator. Fig. 6 illustrates, in sectional plan, a modification of the agitator.

The agitator 1 is of improved design, to more efficiently agitate the liquid, as will be described, and is mounted on a vertical shaft 2. A bracket 3, with a standard 3^a on a base 3^b, supports the operating mechanism. The vessel 4, to hold the liquid operated upon, is supported on the base 3^b, in a depression therein, and is readily removable therefrom. The driving shaft 5 is horizontally journaled in the bracket 3, at the top of the apparatus, and has a crank or handle 6 outside the bracket, for manually operating the separator. The brake 7 is rotatable, and comprises upright slats 7^a embracing the agitator 1, inside the vessel. This brake 7 has the upper arched arms 7^b receiving and holding rigidly the upper ends of the slats

7^a; the lower ends of the slats are held in lower horizontal arms 7^c, which have a stud 7^d extending down and turning in a step bearing 7^e on the bottom of the vessel 4. 60 Above, these arms 7^c have a hub 7^f that has a step bearing 2^f for the vertical agitator shaft 2, at the lower end thereof. This agitator shaft has the bearing for its upper end in the bracket 3, at 2^g.

The upper arched arms 7^b of the brake 7 have a central hub 7^h that receives the reduced hub of a dished bevel gear 7^e. Said arms 7^b, and, consequently, the entire brake 7, are rigidly attached to this gear 7^e, to rotate with it, by means of a thumbscrew 7ⁱ, as here shown. The hollow side of this dished gear 7^e is presented upwardly, and a pinion 2^a is rigidly mounted directly on the agitator shaft 2, within the hollow of the 75 dished gear 7^e. The shaft 5 has two bevel gears 5^a and 5^b, rigidly mounted on it, which mesh with the dished gear 7^e and with the pinion 2^a, respectively, the gears and the pinion being proportioned accordingly. As 80 shown, the dished gear 7^e and its meshing gear 5^a are of equal diameter, and they are, accordingly, miter gears, while the gear 5^b is of the same diameter as the gear 5^a, but proportioned to mesh with the pinion 2^a. 85 The dished formation of the gear 7^e allows the two driving gears 5^a and 5^b to be thus of the same diameter, which is preferred, as it gives a more finished appearance to the apparatus. The necessary provision is that 90 the agitator 1 be rotated faster than the brake 7 rotates, and in the same direction.

The agitator 1 comprises the lower hollow impelling member 1^a, on the lower end of the hollow shaft 1^b. The hollow shaft 1^b has 95 the downwardly furcated hub 1^b that is rigidly secured to the agitator shaft 2 by a thumbscrew, and receives the open upper end of the hollow shaft 1^b in its furcations; thus, air may enter and pass down into the 100 hollow shaft. This open upper end of the shaft is brought high enough, in each instance, to be above the level of the liquid in the vessel. In its extreme upper position, as illustrated, it is somewhat above the upper rim of the vessel 4, allowing the vessel to be completely filled, if desired. However, in practice, the vessel is not completely filled, enough space being left above the liquid to avoid throwing liquid from the vessel by the action of the rotating brake 7. 110

The hollow impelling member 1^a of the

agitator 1, before referred to, may best be described as rectangular, with equal sides, but with the corners or angles removed, or, as illustrated in Fig. 6, as triangular, equilateral, with its angles removed. In either case, being hollow, with relatively thin walls, the removal, or omission, of the corners leaves apertures 1' communicating from the interior of the hollow impeller to the space in the vessel, or to the liquid therein. The lower end of the hollow shaft 1^b being open, the air can circulate down into the interior of the impeller 1^a, and out through the apertures 1' into the liquid in the vessel.

Inspection of Fig. 4 will enable it to be readily understood that the walls of the angular agitator will agitate the liquid outside the agitator, and they will also impel the liquid inside the agitator, acting centrifugally on it, so that it will pass out through the apertures 1', in the direction of the small white arrows. With the rotation of the agitator as indicated by the long arrows, the pressure on the surrounding liquid, outside the agitator, will be substantially in the direction of the small black arrows. It will be understood that the centrifugal impelling effect on the inside liquid, forcing it out of the agitator through the apertures 1', will cause a partial vacuum inside of the agitator, which will, in turn, induce the downward flow of air through the hollow shaft, and out with the liquid, and through the liquid in the main body. The agitation and the universal air currents thus set up are what are desired, and my invention produces them in a peculiarly effective manner, owing to the novel formation of the agitator, just described.

It will be found advantageous to adjust the parts of the agitator so as to regulate the amount of aeration with respect to the amount of agitation. For this purpose, the angular hollow agitator is made with its upper wall detached from its side walls, and adjustably secured thereto by screws 1^c, taking into lugs 1^d on the lower side of the upper wall, and taking through vertical slots in said side walls, to be tightened against said side walls, and hold them stationary in various positions. This upper wall may be rigidly attached, or integral, with the tubular shaft 1^b, and the lower wall, or bottom, simply has an opening in its center through which the agitator shaft 2 passes, and with which it has a close bearing, which thus steadies the lower end of the agitator.

By the adjustment just described, it will be seen that the bottom of the agitator may be made to approach the upper side, diminishing the space inside the agitator, as well as the size of the apertures 1', but, at the same time, the side walls, which do the agi-

tating, are not altered, since they simply move up, outside the upper wall, and present the same surface to the surrounding liquid. Thus, relative adjustment of the agitation and aeration is accomplished in a most simple manner, the parts being economically constructed, and the manipulation and the work of keeping them clean being reduced to a minimum.

As shown, especially in Fig. 2, where the slats of the brake 7 are attached to the arms, these arms are bifurcated to receive the slats between their bifurcations, and, in addition each arm has a slit 7' extending back from the bifurcated part, allowing approach of the parts, so that a screw 7", passing through the arm, across the slit 7', may draw the parts tightly together and clamp the slat. The lower arms 7^c have these screws 7", which may be turned with a screw driver, but the upper arms 7^b have thumbscrews 7'", so that the slats may be readily detached from the arms 7^b, allowing disassemblage of the brake if desired, for cleaning the parts. In the same way, the arms 7^b may be detached from the hub of the gear 7^c, and the hub 1^b, may be loosened from the shaft 2, and the shaft withdrawn. This latter detachment is sufficient to allow separation of the agitator from the brake. The lower part of the impeller member 1^a may be removed from the upper part, allowing access to the interior thereof, and also to the interior of the hollow shaft 1^b, so that all parts may be conveniently cleaned and kept in a sanitary condition.

The bracket 3 is secured to its standard 3^a by having a stud 3' that fits into a socket 3^{a'} on the standard, they having corresponding offsets 3'' that prevent swinging of the bracket on the standard; a thumb-screw 3^{a''} passes up into the lower end of the stud 3' where it extends to the lower open end of the socket 3^{a'}, and bears against the lower side of the socket, clamping the bracket firmly in position. This fastening is loosened, and the bracket raised, when withdrawing the shaft 2 from the agitator and brake, as before mentioned.

For making butter with my separator, either sweet or sour cream may be taken, and a suitable quantity placed in the vessel, at a temperature of about 60 to 65 degrees Fahrenheit, and the apparatus operated for a period of from three to five minutes. After such a period of agitation and aeration, the butter will be separated from the cream and collected in a mass. The residue, containing the non-fatty milk elements, is then withdrawn, a faucet 4^a being provided in the lower part of the vessel 4 for the purpose of conveniently removing liquids from the vessel while leaving the solid substance. However, it is impossible to effect an entire separation of the undesirable milk residues

from the butter by merely decanting after the separating process has been completed. I employ additional steps, amounting to a new process in the preparation of perfectly 5 palatable butter, by granulating it with a purifying aerating agitation, which is performed with the butter mass in contact with a body of pure water.

After all the non-fatty elements have been 10 removed as thoroughly as possible by simple decantation, as above mentioned, I introduce a quantity of pure water at a temperature of about 50 degrees Fahrenheit into the vessel, with the mass of butter that has been 15 left therein, sufficient to submerge the mass. The operation of the apparatus is then resumed, and the agitation and aeration carried on, bringing every particle of the mass into intimate contact with the pure water, 20 with the presence of the circulating air. This results in substantially dissolving the non-fatty elements, or, with respect to the insoluble ones, effecting suspension of such elements in the water, which may be withdrawn, 25 carrying the elements with it. The thoroughness of the purifying action of my process is finally reached when the water, which may be repeatedly supplied afresh, shows no more traces of the milk elements, as 30 it is withdrawn. Agitation and aeration of one or two minutes' duration will result in granulation of the butter mass, and it is in this granulated condition that the operation is carried on to completion, which will require 35 a few minutes' more operation. Such granulation gives the butter the best consistency for the efficient action of the air and water thereon, as before alluded to. When the purifying operation is completed, the 40 granules will float on the water in the vessel, in a neutral condition, and they may then be removed from the surface of the water and worked in any approved manner, the salt being added as desired. The granular 45 consistency of the butter is again of the greatest advantage in the working and salting operations, since it allows the best texture to be imparted to the butter, and the most uniform and intimate incorporation of 50 the salt therewith. The salt may be introduced in solution, if desired, as the granulated butter produced by my process will absorb limited quantities of moisture, for such purpose, with great facility.

55 Other operations upon milk substances are also performed with great advantage with my apparatus, not only where separating is to be done, but in mixing and incorporation, or in the preparation of the substances for 60 such mixing or incorporation. It will also be adaptable for use in arts not involving the use of milk substances, for separating, mixing, agitating, or other treatment of liquid or semi-liquid substances, or emulsions, 65 or pastes.

In any case, the peculiar arrangement of the operative mechanism will exhibit a novel advantage, in that the agitator and the brake rotate in the same direction, at different speeds, and are thus adapted to co-operate and perform their function, that of producing the required agitation of the substance being treated. It is evident that in performing this function, there will be a reaction taking place through the substance, 70 such as the liquid, which will cause the more rapidly rotating part to exert a driving effect on the more slowly rotating one, which will transmit this driving effect to the driving member of the apparatus in the form of assistance in turning the more rapidly rotating one. This results in a balanced action of the device throughout, with all the acting parts in motion, performing the work with the parts moving at a relatively high speed, 75 and therefore with greater mechanical efficiency. Thus, the agitator 1 exerts, through the liquid, a driving effect on the more slowly moving brake, which in turn exerts this effect on the driving shaft 5, assisting 80 the operator in the rapid rotation of the agitator. The effect of the difference between the rotative speeds of the agitator and brake is to produce the desired agitation in the liquid, but with both parts moving. 85 Thus, with the agitator moving at a relatively high speed, the efficiency is manifestly greater than with a stationary brake. This balanced, equalizing action is in accordance with a principle that is original with me, so 90 far as its disclosure has been concerned, and it is here exemplified as a correlative system of energy transmission, with a liquid, or other fluid, or a semi-liquid, as an element or medium of the system. It is apparent that 95 the principle may be present in the operation of devices differing in their minor details, or in their arrangement, and in the purposes for which they are designed. I, therefore, do not wish to be understood as 100 limiting myself to the precise details of construction and arrangement herein set forth, but

What I claim as new and desire to secure by Letter Patent is:

1. In a device of the character described, a rotatable agitator, a rotatable brake embracing the agitator and rotating coaxially with it, a bevel gear with which the brake rotates, a bevel pinion with which the agitator rotates, a driving shaft at an angle to the axis of the agitator and brake, and bevel gears on the driving shaft meshing, respectively, with said gear with which the brake rotates, and with said pinion, said gears and pinions being so proportioned that the agitator rotates faster than the brake does, and in the same direction.
2. In a device of the character described, a rotatable agitator and a shaft there-

for, a rotatable brake with said shaft for an axis, a bevel pinion on said shaft rotating therewith, a dished bevel gear on the brake rotating therewith and embracing said pinion, and bevel gears, coaxial and of equal diameter, meshing, respectively, with the pinion and with the dished gear, for the purposes set forth.

3. In a device of the character described, 10 a hollow agitator adapted to act centrifugally on a substance and agitate it and aerate it by rotation at a relatively high speed, and a brake adapted to coact with the agitator by rotation at a relatively low speed in 15 the same direction as that of the rotation of the agitator, and means for actuating said agitator and said brake, whereby they are correlated through the substance agitated.

20 4. In a device of the character described, an agitator shaft, an agitator, a tubular shaft on the agitator around the agitator shaft and extending upward, and a brake comprising slats embracing the agitator and 25 arms above and below the agitator having axes on the shaft, the arms below meeting in a hub having a step bearing for the shaft, and the arms above meeting in a hub whereby 30 rotative movement may be transmitted to the brake, said arms above being arched upward from said slats to said hub, over the tubular shaft, and actuating means for the agitator and the brake.

5. In a device of the character described, 35 an agitator having a plurality of sides and a top and a bottom, forming a closed box, except at the corners thereof, where there are apertures formed by omission of parts of said sides, bottom and top that would 40 complete the angular formation thereat, and a communicating opening in the top.

6. In a device of the character described, 45 an agitator having a plurality of sides and a top and a bottom, forming a closed box, except at the corners thereof, where there are apertures, formed by omission of parts of said sides, bottom and top that would 50 complete the angular formation thereat, and in the top, where a communicating opening is formed, said agitator having a hollow shaft attached to said top with its interior continuous with said communicating opening.

7. In a device of the character described, 55 an agitator having straight sides meeting a top and a bottom and forming a closed box, except at corners thereof, where there are rectangular apertures formed, and in

the top, where a communicating opening is formed, said agitator also having a hollow shaft attached to said top with its interior continuous with said communicating opening, for the purposes set forth.

8. In a device of the character described, 60 an agitator comprising an upper side and a hollow shaft attached thereto with its interior opening therethrough, and a lower side spaced down from the upper side, and lateral sides attached to the lower and the upper sides, forming a closed box, except 70 at corners thereof, where there are rectangular apertures formed, and means for adjusting the size of said apertures, for the purposes set forth.

9. In a device of the character described, 75 an agitator adapted to act centrifugally on a substance when rotated in it, and to induce air currents through the substance, producing aeration, and means whereby the aeration may be varied without varying the 80 agitation, for the purposes set forth.

10. In a device of the character described, 85 an agitator having an upper side, with means for rotating the agitator and for admitting air below said upper side, attached thereto, a lower side spaced down from said upper side, lateral sides secured to the lower side, leaving apertures at the corners and extending up and embracing said upper side at its edges, lugs on the lower surface of the 90 upper side of the agitator, and screws taking into the lugs, said lateral sides having upright slots through which the screws take into said lugs, the screws being adapted to clamp the lateral sides to the edges of the 95 upper side, in various adjusted positions, for the purpose set forth.

11. In a device of the character described, 100 an agitator of box-like formation with apertured corners, and a hollow shaft extending up from its top with its interior communicating with the interior of the box-like agitator, a shaft extending through the hollow shaft, and through the bottom of the box-like agitator, which makes intimate contact 105 therewith to steady the lower end of the agitator, a furcated hub on the upper end of the hollow shaft, said upper end being open, and said shaft extending through the hub, and means for securing the hub to the 110 shaft, for the purposes set forth.

ALPHEUS FAY.
